H. MOYER

TOY

Filed Sept. 26, 1925

Howard Moyer.

F. V. Winters

Attorney

UNITED STATES PATENT OFFICE.

HOWARD MOYER, OF BROOKLYN, NEW YORK.

TOY.

Application filed September 26, 1925. Serial No. 58,788.

This invention relates to toys and more particularly to self-rolling toys.

The principal object of the invention resides in the provision of means within the 5 toy, comprising a body portion, which latter, when rotated, will store up energy in said means and then consume said stored energy by propelling the toy in the opposite direction to said rotation.

10 Another object is to provide means for alternately rotating the toy operable from the body portion of said toy.

A further object of the invention is the 15 production of a simple and durable toy, inexpensive to manufacture and possessing the necessary attractiveness to assure its commercial success.

With the foregoing objects in view my 20 invention consists in certain novel features of construction and combination of parts, which will be hereinafter described, and pointed out in the claims.

In said drawings:

Figure 1 is a sectional view through the 25 body of the toy and the housing of its operating mechanism, being taken substantially on the line 1—1 of Fig. 2.

Fig. 2 is a sectional view taken substantially on the line 2—2 of Fig. 1.

30 Fig. 3 is a sectional view, like unto Fig. 1, illustrating a slightly modified form of structure, said section corresponding substantially to the section line 3—3 of Fig. 4.

Fig. 4 is an enlarged sectional view taken 35 on the line 4—4 of Fig. 3, illustrating the association of parts constituting the operating mechanism, and

Fig. 5 is a sectional detail illustrating the 40 means of coaction between said operating mechanism and the body of the toy.

Essentially, the embodiments of my invention, as illustrated in the drawings, comprises a body portion 5, a housing 6, loosely mounted on a shaft 7, fixedly secured to 45 the sides of said body portion 5, said housing 6 supporting a tensioning device in the form of a coiled spring 8, which latter is adapted to communicate energy to said shaft 7, for rotating said body portion, 50 through the medium of a train of gears, as will presently appear.

On inspection of the drawings it will be 55 observed the said body portion 5 is entirely closed and provided with opposed socket members 9, adapted to receive the squared ends of said shaft 7. Said housing 6 is

loosely suspended from said shaft and is provided with a counterweight 10 to maintain the same in depending position with respect to said shaft and substantially within the vertical axis of said body portion.

As will be seen in the drawings the center of gravity of the weight 10 lies to one side of the vertical plane passing through the axis of the shaft 7. This condition prevails 65 when the spring 8 is wound up tight and when the body is rolling upon a surface, as will be hereinafter explained.

Passing now to the operation of the toy, and considering Figs. 1 and 2, let us assume 70 that spring 8 is to be brought under tension, or, in other words, energy is to be stored within the operating mechanism. The toy

may now be held in the hands and bodily rotated in the direction of the arrow (Fig. 75 1), whereupon rotation of the shaft 7 and gear 11, mounted thereon, is communicated to said spring 8 connected to gear 12 on shaft 13, by means of the gears 14 and 15,

carried by the intermediate shaft 16. Sufficient energy having been accumulated in 80 said spring 8, the toy may now be placed on the ground or floor, whereupon the consumption of said energy causing the toy to rotate or roll in a direction opposite to the

winding rotation until said energy is exhausted. It is, of course, understood that 85 during this latter operation, the housing and its inclosed mechanism remains in pendant position. In order that the spring may dis-

90 pense its energy uniformly I prefer to provide my device with governor means 17 operable by gear 14 and gears 18 and 19 carried by shaft 20, as clearly shown in the drawings.

95 During the rolling movement of the body 5, and as the spring 8 unwinds, the center of gravity of the weight 10 will move toward the vertical plane passing through the axis of the shaft 7 and consequently the spring 100 8 will be kept in a taut condition and the body 5 will continue to roll over a plane surface until such time when the center of gravity of the weight lies in the vertical plane of the axis of the shaft 7. Thus the 105 body will have maximum rolling movement.

In the modification illustrated in Figs. 3 and 4 I introduce a feature for imparting an alternating rotative motion to the toy. That is, I provide means for rotating the 110 toy in one direction and further means for reversing the rotation and permitting the

return of said toy to substantially its starting point and repeat these operations one after the other.

The method of storing energy within the 5 operating mechanism, is, of course, similar to my preferred form, so that the description of the structure and its mode of operation now to follow, will begin at a point with the spring 8 under tension.

10 The housing 21 is suspended from the shaft 7 and contains the spring 8, connected to gear 12 carried by shaft 13. Thus, in the position indicated in Fig. 3, motion from said spring 8 and gear 12 is communicated 15 to gear 11, fixed to shaft 7 by means of the intermediate gear 22. The rotation of the toy is now indicated by the arrow, which is continued until the spring-pressed detent 23 strikes against the lower end of the shiftable 20 lever 24, whereupon the gears 25 and 26 connects said gears 12 and 11 oppositely rotating the latter. This reversed rotation is continued until the detent 23 engages the other side of said lever 24 to bring gear 22 25 in mesh with gear 11 and the reversal of the rotative movement of said toy continued until the energy in the spring is exhausted.

As noted in the drawings said lever 24 is provided with upstanding arms 24^a and 24^b, 30 the latter carrying shaft 27 supporting gear 22, while the former supports a pair of shafts 28 and 29 carrying gears 25 and 26 respectively. The housing 21 is provided with arcuately slotted ears 30 for further 35 supporting said shafts 28 and 29 and a similar slot for supporting shaft 27. Said lever 24 is pivotally carried by shaft 13, while breaking the connection between gears 11 and 22 and between gears 11 and 26 and 25, 40 does however, always maintain the enmeshment of gears 22 and 25 with gear 12 so that the shifting engagement with said gear 11 is easily facilitated.

To assure the positive enmeshment of the 45 gears and their maintenance in this position during the operation of the toy, I provide spring clasps 31 and 32 which lightly engage the lower portion of said lever 24 and read-

ily released therefrom by the action of said 50 detent 23.

In order that the detent 23 may not interfere with the rotation of the body portion during the winding operation I provide said 55 detent with a finger grippable head whereby said detent may be retracted and rotated without interfering with the lower portion of the lever 24.

It is of course to be understood that I reserve unto myself the right to make slight 60 modifications and changes in my invention, all of which being within the spirit of the invention and falling within the scope of the appended claims.

I claim:

1. A toy comprising a rotatable body, a 65 shaft fixed at the centers of the opposite end walls thereof, a gear fixed to the shaft, a housing pivoted to the shaft, a gear carried by the housing, a spiral spring connected with the housing and the last mentioned gear, a lever pivoted upon the housing and having spaced arms, gears carried by the arms and meshing with the gear upon the housing, said gears adapted to mesh alternately with the gear upon the shaft as 70 the lever is rocked and a detent carried by the body and disposed in the path of movement of the end portion of said lever.

2. A toy comprising a rotatable body, a shaft fixed at the centers of the opposite 80 end walls thereof, a gear fixed to the shaft, a housing pivoted to the shaft, a gear carried by the housing, a spiral spring connected with the housing and having spaced arms, gears carried by the arms and meshing 85 with the gear upon the housing, said gears adapted to mesh alternately with the gear upon the shaft as the lever is rocked, resilient means carried by the housing for maintaining the respective gears in enmeshment 90 during the operation of the toy and a detent carried by the body and disposed in the path of movement of the end portion of said lever.

In testimony whereof I affix my signature.
HOWARD MOYER.
